(57) CLAIM

The ornamental design for a vehicle, as shown and described.

DESCRIPTION

FIG. 1 is a front, right side perspective view of the vehicle of the present invention;

FIG. 2 is a front, left side perspective view thereof;

FIG. 3 is a rear, right side perspective view thereof;

FIG. 4 is a rear, left side perspective view thereof;

FIG. 5 is a right side view thereof;

FIG. 6 is a left side view thereof;

FIG. 7 is a front view thereof;

FIG. 8 is a rear view thereof;

FIG. 9 is a top view thereof;

FIG. 10 is a bottom view thereof; and,

FIG. 11 is a top view of a second embodiment of the vehicle of the present invention.

All other views of the second embodiment are the same as in the first embodiment in FIGS. 1-8 and 10.
